VOTING MACHINE

Frank Conrad, Wilkinsburg, Pa., assignor to Westinghouse Electric & Manufacturing Company, East Pittsburgh, Pa., a corporation of Pennsylvania

Application March 4, 1939, Serial No. 259,852

3 Claims. (Cl. 235—55)

This invention relates to voting machines and particularly to a voting button mechanism.

One object of my invention is to provide a voting button mechanism to permit the casting of a vote and to prevent more than one vote by the individual voter, and to prevent damage to the voting machine mechanism in case the voter tries to force the button in order to cast more than one vote by that button.

Another object of my invention is to make it impossible for a voter to vote more than once for the same candidate if such candidate is endorsed by different parties.

Another object of my invention is to adjustably limit the total number of candidates which can be voted upon.

In the design of machines for mechanical vote recording, it is necessary to incorporate certain features which will preclude the possibility of a voter casting an illegal vote; that is, voting more than once for any candidate, or voting more than the proper number of candidates for any particular office. In various voting machines that have been designed, and in some of those now on the market, there are provisions incorporated which lock certain buttons after other voting buttons have been turned.

Since a voter might apply considerable force to some of the voting levers, it is necessary to so arrange the locking devices that no damage can be done accidentally or intentionally by the voter.

In order to prevent the application of excessive forces to any parts of the counting or voting mechanism, I provide a releasing ratchet device in the voting button itself. That ratchet device transmits a definite and limited torque to the voting shaft and thus permits the usual locking devices for the voting mechanism to be considerably simplified.

After each voting operation is performed, the button is returned to its initial position when the machine is reset. As a result, no indication is left by the position of the button to show how a voter has voted. At the same time, the button is marked for the convenience of the voter so that he can tell, while he is still voting, what buttons he has voted according to the marked index on the button.

The application of this voting button mechanism to a voting machine allows a very great simplification of the interlocking features usually required. Thus, in the case of machines employing old designs, for example, it is necessary to incorporate quite an elaborate interlock to prevent a party lever being thrown after an indi-

vidual button has been voted, or vice versa, to prevent other individual candidates being voted after a complete party ticket has been voted. With the mechanism described above any number of individual candidates can be voted, the voter can then pull any one of the party levers and the effect will be to vote only for those offices for which individual candidates have not been voted. The necessity of this interlock on the present well known machines requires a slip clutch mechanism for the party lever to prevent breaking of any shaft of an individual candidate which the voter has voted for before pulling the party lever, and in view of the fact that this slip clutch on the party lever has to give sufficient torque to vote the complete roll of voting stations and at the same time not damage an individual voting button which at the time is in operated position, a comparatively delicate adjustment of the clutch is required.

For primary elections it is necessary to lock out all voting rows except that of the party for which the voter is registered. This in general has required a rather complicated mechanism.

With the present device for the primary election the curtain enclosing the voter would be attached to the left side of the machine at a point inside the straight party levers; i. e., the straight party levers would not be accessible to the voter, but would be in view of persons outside the voting machine curtain. In operation the levers would all be turned to the left so that the bottom horizontal party operating bars would be thrown over to a position where they would interfere with the pin on the pawl carrying lever, thus preventing this button from being voted. To permit the voter to vote, the lever for the particular party for which he is registered, would be moved to the middle position, thereby permitting the selection of candidates in a certain row or rows.

A voting button mechanism constructed in accordance with the principles of my invention is illustrated in the accompanying drawings, in which:

Fig. 30 is a rear elevational view of the counting bar assembly shown in a non-operated or non-voted position.

Fig. 31 is a rear elevational view of the counting bar assembly in which the upper button is in a non-operated position whereas the lower button is in an operated position; and

Fig. 32 is a front schematic view, partly broken away, of a complete voting machine.

As illustrated in the drawings, a voting button mechanism 1 comprises a vote counting shaft 2, a ratchet disc 3, a pawl 4, an operating crank arm 5 carrying a pawl biasing spring 6, and an

actuating button head 7. A restoring biasing spring 8 is also provided to exert a restoring force upon the button mechanism.

The vote counting shaft 2 serves to transmit the torque from the actuating button head 7 to a voting or reset bar 11.

The shaft 2 embodies a circular portion 12, an adjoining square section 13 for receiving the ratchet disc 3, then a circular portion 14, and two stop gear portions 15 and 16, another circular portion 17, and a square end 18. The purposes and functions of the various portions of the shaft will be referred to as the description proceeds.

In the arrangement that is shown in Figs. 1 and 3, the shaft 2 extends forwardly through a hole in the wall panel 19 of the voting machine, with the round portion 14 of the shaft in the space of the wall panel. The square portion 13 of the shaft is located in front of the wall panel 19 and supports the ratchet disc 3 and operatively interconnects the ratchet disc 3 and the shaft 2 through the square shank portion 13 and the square opening 21 of the disc 3. The disc 3 fits the square shank portion 13 with a sliding but not loose fit to permit easy assembly and separation. The round front portion 12 of the shaft 2 serves as a stud bearing for the hub 45 of the crank arm 5 shown separately in Figs. 10, 11 and 12. The gear stop portion 15 of the shaft cooperates with the toothed rack edge section 22 of the voting bar 11 disposed at the rear of the wall panel 19. The gear stop 16 cooperates with a pair of rollers 20 mounted on levers 24 which levers are pivoted on bearing plate 25 at pivots 24a as shown in Fig. 25.

The shaft 2 serves thus as an actuating device or torque transmitter for the voting button mechanism, and serves also as a support for the button head and for the ratchet mechanism mechanically connected between the button head and the shaft.

The ratchet mechanism includes the ratchet disc 3 of Figs. 6 and 7, the pawl 4 of Figs. 8 and 9, and the crank arm 5 of Figs. 10, 11 and 12, the biasing spring 6 on the crank arm 5 to maintain the pawl 4 in engagement with the ratchet disc 3, and a return biasing spring 8 to bias the crank arm 5 to its initial position.

The ratchet disc 3, as shown in Figs. 6 and 7, consists of a washer disc provided with a square central opening 21, and four equally peripherally spaced, similarly shaped, channel notches 3a, 3b, 3c, and 3d. Each channel in the ratchet disc consists of a relatively flat lease, and one side wall 26 substantially radial and the other side 26a somewhat curved but sloped from the base at an angle greater than a right angle. All of the channel notches are equally spaced and similarly disposed around the periphery of the disc, i. e., with the radial wall in the forward or actuating direction.

The pawl 4, shown separately in Figs. 8 and 9, consists of an operating arm 31 with a finger 32 on one side of a pivotal bearing opening 33, and consists also of an operating arm or handle 34 on the other side of the pivotal bearing opening 33. The operating arm 34 supports a stop pin 35 which serves as a stop for the biasing spring 6 on the crank arm 5, in order to initially bias that spring.

The crank arm 5, as shown separately in Figs. 10, 11 and 12 consists of a central hub 45, from which two arms 38 and 39 extend radially in opposite directions. Two crank pins 41 and 42 are respectively mounted on the arms and extend

laterally therefrom near the ends of the arms 38 and 39, parallel to the main axis.

The hub of crank arm 5 comprises an externally cylindrical boss 44 at one side and a polygonal boss at the other side. The hub is provided with a cylindrical opening transverse of the crank arm 5 for receiving the stud bearing 12 of shaft 2 to thus provide a pivotal support for the crank arm 5.

When all parts are assembled the boss 44 presses against ratchet disc 3 to hold it in axial position on the square portion 13 of shaft 2. The polygonal boss of the hub is adapted to receive the similarly shaped opening in the actuating button head 7.

We may now assemble the voting button mechanism of Figs. 1 to 16, inclusive. When the shaft 2 is extended through the wall panel 19, a thin metallic washer 9, preferably of copper or bronze, fits on the cylindrical portion 14 of the shaft and rests against the front surface of the panel 19. This washer 9 serves as a spacer between the panel 19 and the ratchet disc 3 to prevent scarring of the wall surface of the panel 19 by the sharp edges of the disc 3 during its operation. The ratchet disc 3 with its radial walls in a clockwise direction with respect to its curved walls as viewed from the front of the panel is then placed in position on the square portion 13 of the shaft 2. The pawl 4 is then assembled on crank pin 41 of crank arm 5 with its finger 32 clockwise as viewed from the front and with the stop pin 35 on the outside of the long narrow leaf spring 6, so that the leaf spring 6, by its pressure against the stop pin 35, will tend to rotate pawl 4 clockwise as viewed from the front and to press the latching pawl finger 32 radially inward, around the pivot opening 33 and the pin 41 as pivotal centers as will appear in Fig. 2. Finger 32 will thus be biased to move into one of the notches of the ratchet disc 3. The crank arm 5, as a unit, with the pawl 4 so mounted, is then slipped onto the circular portion 12 of the shaft 2, and the operating arm or handle 34 of the pawl is momentarily manually pressed downward or inward against the normal direction of the force of the biasing spring 6, to permit the pawl finger 32 to clear the edge of the disc 3 and to move into one of the notches. Before the crank arm 5 with its supported pawl 4, as a unit, is placed in position on the bearing portion 12 of the shaft 2, the biasing spring 8 is placed in position to encircle the boss 44 on the crank arm 5, within the space under the leaf spring 6 and between the pawl 4 and the crank arm 5 as will appear in Fig. 2, one free end 8a of the spring 8 is positioned to engage the side surface of the crank pin 41, and the other end of the spring 8 is provided with an eye 8b to fit over a stationary pin 8c mounted on the panel wall 19 adjacent the button assembly. The ratchet unit is now assembled in operative position and is ready to receive the actuating button head 7 of Figs. 13 and 14. As shown in those figures, the button head 7 is provided with a metallic insert having a squared central opening 46 of proper size to provide a sliding fit over the squared hub 45 of the crank arm. The metallic insert also embodies a flange 47 that rests against the back surface of the button head. The flange 47, in turn, supports an integral spaced flange 48, that is spaced from the base flange 47 to provide a peripheral right angle channel space 49 between flange 48 and the back surface of the button head. The purpose of this

space is to receive a locking strip 50 that will hold the button head axially in place on the hub 45 while permitting the button head and thus the crank arm 5 to be rotated through an angle of 90° to actuate the ratchet mechanism. The hooked end of locking strip 50 forms a spring clip which fastens to the edge of panel 19 as shown in Figs. 20 and 22.

Before mounting the button head on the ratchet assembly for each voting button, however, a cover 51 is placed over the ratchet assembly, with an opening 52 in the cover coaxially aligned with the button shaft 2, so that the button head may be inserted into the opening 52 to fit over the square hub 45 of the crank arm as appears in Figs. 20, 21 and 22. After the button has been so located, the positioning and holding strip or bar 50 is moved longitudinally into place along the rear wall of the cover 51 on a shoulder 54 until the bar 50 moves into and through the peripheral channel 49 on the back of the voting button where the button extends through the cover 51. Referring to Figs. 25 and 26 a pair of levers 24 are pivoted at 24a on bearing plate 25. A spring 23 connecting the upper parts of the levers tends to keep rollers 20 in the depressions of gear 15 so as to normally position gear 15 in the manner shown in Fig. 25 in order that it will not interfere with reset bar 11 during reset operation.

Operation of voting button

The operation of the voting button and its associated mechanism may be best understood by referring to Figs. 2, 28 and 29. Fig. 28 shows the position of the ratchet mechanism when the voting button is in its initial or non-voted position. Assume now that it is desired to vote the particular button. This voting is effected by turning the button clockwise, which is tantamount to turning the crank arm 5 clockwise inasmuch as the button has a square opening 46 which fits over the substantially square portion of the hub 45. This clockwise movement of crank arm 5 will transmit a force through pin 41 and effect a clockwise movement of pawl 4 and since pawl 4 has its finger 32 biased into engagement with a notch in ratchet disc 3 by virtue of the force of spring 6 which tends to rock pawl 4 about pin 41 as a pivot, it will effect rotation of ratchet 3. The rotation of ratchet 3 will effect rotation of the vote counting shaft 2, thus registering a vote in a vote counting mechanism (not shown). Fig. 29 shows the button mechanism in its operated or voted position, that is, after the button has been turned nearly through its limit of angular movement of 90°. The button cannot be moved more than 90° because of stop member 53 which is located on panel 19 and which abuts crank arm 5 in the event that a clockwise movement of more than 90° is attempted. Besides its function as a stop member, element 53 acts as a support for cover plate 51 since it is screw threaded internally, thus accommodating a screw which is driven therein from the exterior of the cover plate. Similarly a counterclockwise stop is effected by a pin 70 which will abut pawl 4 inasmuch as the pin 41, which is the point of support of pawl 4, is more remotely situated from shaft 2 than is pin 70. This pin 70 extends through a slot 71 in the panel and is rigidly fastened to a vertically slid able cam member 65 which will be described more fully later, suffice it to say for the present that pin 70 moves upwardly with the voting or reset bar 11 when the

button is turned clockwise and is caused to move downwardly with bar 11 when the latter is moved downwardly to effect reset of the machine. Assume now that it is desired to reset the button mechanism which is now in the voted or operated position shown in Fig. 29. Pin 70 is moved downwardly with reset bar 11 and during its downward movement it will press against the cam surface of pawl 4 and cause the pawl to move counterclockwise about pin 41 as a pivot overcoming the resisting force afforded by spring 6. Thus finger 32 will become unseated from its coacting notch in ratchet disc 3 and at the moment of such unseating, spring 8 will be free to rotate the crank arm 5 and pawl 4 counterclockwise (see Fig. 2) into its initial position, that is, into the position shown in Fig. 28. The ratchet disc 3, however, does not move counterclockwise inasmuch as finger 32 of the pawl merely rides over the outer surface of ratchet 3 and does not drive the ratchet. Thus the vote counting shaft 2 retains its actuated or voted position and retains its vote registering effect in the vote counting mechanism (not shown) even though the crank arm and pawl are reset to their initial position. It will thus be seen that each time the button is voted and the machine is reset the vote counting shaft will be moved another 90° clockwise and the total number of votes recorded by the vote counting machine will be the number of revolutions of vote counting shaft times four.

It is impossible to vote more than once during one setting of the machine because while it is possible, after having turned the button clockwise to its voted position to thereafter turn the button counterclockwise, this latter movement has the effect of cancelling the vote previously made because the pawl 4 is biased by spring 6 to effect seating of finger 32 in the notch in ratchet disc 3 hence counterclockwise movement of crank arm 5 will drive and effect counterclockwise movement of ratchet disc 3 and incidentally will also effect a downward movement of the voting or reset bar 11 as will be explained more fully hereinafter.

Operation of party lever

The operation of the party lever and its associated mechanism can be best understood by referring to Figs. 20, 21 and 27 wherein reference character 63 denotes a party lever, the rotation of which is effective to operate all the candidate buttons in a horizontal row to effect a "straight party" vote. Although only one button is shown in Figs. 20 and 21, it must be remembered that in a complete machine, as shown in Fig. 32, there are a number of buttons in a horizontal row for each particular party, each button representing a different candidate belonging to a particular party. In Figs. 20 and 21 party lever 63 (shown dotted), is removed for the sake of clarity of its driving mechanism. Fig. 27 shows the parts which may be located in front of the panel. In Figs. 20 and 21 the square shaft 72 has integrally connected therewith a gear 62. The hub of party lever 63 has a square opening which snugly fits over square shaft 72 and is rigidly secured thereto by a screw 73. Gear 62 engages a party rack 61 hence when party lever 63 is rotated clockwise it causes rack 61 to move to the left. By virtue of the edge 64a of a cut away portion 64 of rack 61, such movement to the left will cause edge 64a to engage pin 42 of crank arm 5 and effect clockwise rotation of crank arm 5. For each of the buttons located along rack 61 there is a similar

cut away portion as shown in Fig. 32, hence when the party lever 63 is turned clockwise into the position shown in Fig. 21, the effect will be to turn all of the buttons located in the same horizontal row, in other words, referring to Fig. 32 if the "Democratic" party lever is turned clockwise from the position shown its effect will be to register a vote for each of the candidates Mr. A, Mr. B, Mr. C and Mr. D, thus voting a so-called "straight party ticket." After a "straight party ticket" has been voted, as shown in Fig. 21, it is impossible to unvote any of the actuated buttons in the "Democratic" horizontal row because now the crank arm 5 is locked by stop member 53 from clockwise movement and is locked against counterclockwise movement by the upper edge of rack 61 which abuts pin 42 of the crank arm.

For primary elections it is necessary to lock out all voting (horizontal) rows except that of the party for which the voter is registered. This has in the past required a rather complicated mechanism. In accordance with my invention, for primary election voting the curtain enclosing the voter (not shown) would be attached on the left side of the machine at a point immediately to the right of the party levers; i. e., the party levers would not be accessible to the voter, but would be in view and under control of an official outside the voting machine curtain. In operation all the party levers except the one registered for would be turned to their extreme left position. While such party levers are being turned to their left positions, each of the party racks 64 will move to the right and edge 64b thereon will strike the lower tip of pawl 4 (see Fig. 20) causing the finger of pawl 4 to be unseated from its corresponding notch in ratchet disc 3 and as long as the upper edge 64d engages pawl 4 the pawl will be out of driving engagement with ratchet 3. In the extreme left position of the party lever, surface 64c will be immediately adjacent pawl 4, hence if the button is turned it will be ineffective to register a vote, first because of the unseating action of surface 64d, then, after further rotation of the button, because of the retained unseating action of surface 64c with respect to the pawl and ratchet. The party lever which corresponds to the party for which the party is registered is placed in the operative position, that is, in the position shown in Fig. 20. In this position there is no part of rack 61 which will resist clockwise movement of the button assembly.

Operation of reset bar

The operation of the voting or reset bar 11 will be more readily understood by referring to Figs. 17 to 19 and 21 to 27, inclusive. As shown in Fig. 24, a bolt 55 is screw threaded to the back of panel 19 just below slot 71. A spring 67 surrounds the bolt and has one end abutting the end of the bolt and the other end pressing against a washer which contacts a vertically slidable cam member 65 (through which extends bolt 55 as shown in Fig. 24), the shape of which cam is more clearly shown in Fig. 18. Cam member 65 has a pin 70 which extends through a slot in reset bar 11 and through slot 71 and has a pair of lugs 74 which are slidable along the outer edges of reset bar 11. Spring 67 will press against cam 65 of cam member 65. A lock member 75 is mounted on cam member 65 and is slidable thereon through lugs 68 of the cam member as shown in Fig. 19. The lock member 75 has a pin

78 which projects through groove 79 of the cam member 65 and terminates just on the rear surface of the panel (see Fig. 23). Lock member 75 also has an internally threaded stud 77, the purpose of which will be described further on. Lock member 75 has an outstanding lug 78 which may or may not cover a notch 69 in the cam member depending on the operation of the device. As shown in Fig. 27 reset bar 11 is movable vertically in increments which correspond to the space between the notches on bar 11. The reset bar is held in position by a spring biased member 60 (Fig. 27) which is mounted on the panel and which comprises a pair of members pivoted at their lower ends and having rollers 59 at their upper ends which are held seated in the notches by spring 58. In order to avoid overtravel of reset bar 11 as the result of the jerk applied to it by the voting button, a dashpot 57 is also mounted on the panel and is connected to the reset bar through an arm 56.

The operation of the reset bar and its associated mechanism is as follows.

Assume that the machine is in its reset or initial position. In this position the reset bar and its associated mechanism will appear as in Fig. 30, that is, the outstanding lug 78 on lock member 75 is situated below notch 69 of cam member 65, hence when the button is turned (i. e. voted), gear 15 will turn and one of its teeth will project into notch 69 of the cam member and since notch 69 is in registry with one of the notches in reset bar 11 gear 15 will drive both the cam member 65 and reset bar 11 upwardly. Lock member 75 will also move upwardly since the lower part of groove 79 will push up against pin 76 and carry the lock member 75. The cam member and lock member will be held in this upper position by spring 67 since it now engages the lower part of cam 66 as shown in Figs. 23 and 24. Reset bar 11 can be moved upwardly by other buttons on a vertical row without disturbing the cam member and lock member inasmuch as bar 11 has extended grooves which clear all the pins 70. In other words after a button has been voted which effects a predetermined upward movement of reset bar 11, other buttons on a vertical row can, by operation, move reset bar 11 upwardly still further, by the same increment per button, bar 11 being held in operated position by rollers 59. Thus if three buttons are voted in the same vertical row, reset bar 11 will be moved upwardly by three increments hence the total upward movement of reset bar 11 is a measure of the number of votes which have been cast in a vertical row.

In order to reset any of the buttons in a particular vertical row, it is necessary to move reset bar 11 downwardly which may be done manually. Gears 15 and 16 are normally held in position as shown in Fig. 25, by virtue of levers 24 pivoted at 24a to plate 25, which levers have mounted thereon rollers 20 which are seated in the depressions of gear 16 by the force of spring 23 hence the downward movement of reset bar 11 has no effect on gear 15, thus it will permit voting counting shaft 2 to retain its voted position, however, the downward movement of reset bar 11 causes its cross piece (shown in cross section in Fig. 24) to strike against pin 76 causing lock member 75 to move downwardly, and pin 76 strikes against the lower edge of groove 79 of cam member 65, causing downward movement of the cam member and pin 70 thereon. If a number of buttons in the same vertical row are to be reset simultaneously, other pins such as 76 are moved down-

wardly by corresponding cross pieces. The downward movement of pin 70 releases pawl 4 to permit it to slip back a notch on ratchet disc 3, as explained before, and effects resetting of all the buttons in the vertical row, that is, movement to their original positions without disturbing the voted positions of the vote counting shafts 2.

Referring to Fig. 32 it will be seen that in order to reset the entire machine, a spring biased stop element 89 is turned counterclockwise so as to make it possible to manually move horizontal bar 90 downwardly against the tension of its supporting springs 91 and 92 by rotating crank 95. As bar 90 is pushed downwardly it strikes against the top of each of the reset bars 11, thus effecting reset of all the buttons of the machine, at the same time, a vertical rack 93 is moved downwardly and since its teeth engage the outer gear segments 94 of the party operating levers, it will restore party operating levers to their initial position as shown in Fig. 32.

Operation of vote limiting device

The operation of the vote limiting device may be best understood by referring to Fig. 32. As explained hereinabove, each time a button is voted, reset bar 11 is moved upwardly a definite increment and the total upward movement of reset bar 11 is a measure of the total votes registered in a particular vertical row. Hence if it were desired to limit the number of votes which can be voted in a particular vertical row, all that would be necessary would be to have a stop means to limit the upward movement of rack bar 11 so that gear 15 cannot drive rack bar 11. Such stop means is denoted by a pair of stepped wedge elements 81 and 82. Wedge element 81 is rigidly fastened to reset bar 11 while wedge element 82 is loosely mounted on bolts 84 which bolts are rigidly secured to a support 83 which may be mounted on the panel. Wedge element 82 has two horizontal grooves 85 thereby permitting lateral movement of wedge element 82 with respect to bolts 84 which lateral movement is effected by the upward movement of wedge element 81. Wedge 82 will not only limit the upward movement of wedge 81 but will limit also the upward movement of wedge 86, as will be obvious. Furthermore, wedge 82 will limit the movement of both wedges 81 and 86 only when the sum of the votes of row W and row X corresponds to the particular vertical position of wedge 82. This will be understood more clearly from the following analysis. Assume that wedge 82 is adjusted vertically by placing bolts 84 in suitable holes on support 83 so that it is to limit the sum of votes of rows W and X to four. If row W and row X are each moved upwardly by two increments resulting from two votes in each row then wedges 81 and 86 at their limiting position will move wedge 82 so that bolts 84 will be centrally located with respect to grooves 85. Suppose, however, that three votes have been voted on row W. In this instance wedge 81 at its uppermost position will force wedge 82 to move more towards the right with respect to bolts 84. It will be noted, however, that the effect of this movement to the right will be to restrict the upward movement of wedge 86, that is, wedge 86 will be able to move only one increment (corresponding to one vote), further upward movement being restricted by the steps of wedge 82. In carrying this analysis still further, it will be seen that by vertical adjustment of all the upper wedges, that is, wedges 82, 81 and 88 the total votes registrable on the machine can

be restricted to any desired amount. For example, if the maximum number of votes permissible is one complete horizontal row, that is, a "straight party ticket" then each of the wedges 82, 87 and 88 are at the same height so as to allow only one straight party vote for each of the rows W, X, Y and Z.

After a voter has exhausted the number of votes to which he is entitled thus effecting a locking of the reset bars by the wedges, if he thereafter tries to cast an illegal vote, that is, if he thereafter turns any of the voting buttons, the reaction caused by the locked reset bars will overcome the force of springs 6 and cause the pawls 4 to slip over the ratchet disc 3 to the next notch, thus although the button can be turned the voting shaft is not turned, hence no vote is registered. This slipping of the clutch is aided by the unseating effect, by pins 70, of the pawl from the ratchet teeth.

Operation of endorsed candidate limiter

It frequently happens, for example, in the case of voting for judges that the same candidate is endorsed by different parties. In such cases the law has been that the same candidate must not be voted upon more than once, that is, he must not be voted first in one party row then in another party row. In order to make it impossible for a voter to vote twice for the same candidate, that is, in different party rows lock member 75 is employed in the following manner. Referring to Fig. 31 it will be seen that Mr. E is endorsed by both the Republican and Labor party. In order to make it impossible to vote more than once for Mr. E, the lock member 75 associated with Mr. E of the Labor party button and the lock member 75 of Mr. E of the Republican party are both secured through their screw threaded studs 77 to a strip 96 by means of screws 97 (see Figs. 24, 30 and 31). Assume now that Mr. E has been voted on in the Republican party row, as shown in Fig. 31, thus the upper lock member 75 has been moved upwardly and since it is connected to strip 96 and since the lower lock member 75 is also connected to strip 96, both lock members will move upwardly at the same time. The upward movement of the lower lock member 75 has the effect of covering notch 69 of the cam bar (compare Figs. 31 and 30). Hence it is impossible now to vote for Mr. E in the Labor party, since it is impossible to turn gear 15.

I am, of course, aware that others, particularly after having had the benefit of the teachings of my invention may devise other forms of voting machines embodying my invention and I, therefore, do not wish to be limited to the specific showings made in the drawings and the descriptive disclosure hereinbefore made, but wish to be limited only by the scope of the appended claims and such prior art that may be pertinent.

I claim as my invention:

1. A voting mechanism comprising a counter actuating shaft to operate a counter, a ratchet disc secured on the shaft and provided with several peripheral ratchet recesses of channel section transverse to the plane of the disc, an operating crank-arm rotatably pivoted on the shaft adjacent the disc, a pawl pivotally mounted on a

crank-pin on the crank-arm, said pawl embodying a finger on one side of the crank-pin to extend into the channel recesses of the ratchet disc and a handle on the other side of the crank-pin to turn the pawl arm about the crank-pin, a leaf spring anchored on the crank-arm and engaging the pawl handle to bias the pawl finger into or towards the channel recesses of the ratchet disc, and a button-head mechanically connected to the

10 crank-arm to rotate the arm.

2. In combination with a stationary panel voting mechanism comprising a counter actuating shaft to operate a counter, a ratchet disc secured to the shaft and provided with several peripheral ratchet recesses of channel section transverse to the plane of the disc, an operating crank-arm rotatably pivoted on the shaft adjacent the disc, a pawl pivotally mounted on the crank-arm, said pawl embodying a finger on one side of the pivot to extend into the channel recesses of the ratchet disc and a handle on the other side of the pivot to turn the pawl arm about the pivot, and a leaf spring anchored on the crank-arm and engaging the pawl handle to bias the pawl finger into or towards the channel recesses of the ratchet disc,

15 20 25 30 35

a coil spring having one end anchored on said panel and the other connected to said arm so as to be wound as the result of rotation of said counter actuating shaft during voting, resetting means for engaging said pawl to allow unseating of said pawl from its corresponding ratchet recess thereby allowing it to move in a direction opposite that in which it was rotated, under the influence of the energy stored in said wound coil spring and assume engaging relationship with a different ratchet recess in a position clear of said resetting means without affecting the position of said rotated shaft and stop means on said panel for restricting angular movement of said pawl.

40 45 50 55 60 65

3. A voting mechanism comprising a counter actuating shaft to operate a counter, a ratchet disc secured to the shaft and provided with several peripheral ratchet recesses of channel section transverse to the plane of the disc, an operating crank-arm rotatably pivoted on the shaft adjacent the disc, a pawl pivotally mounted on a crank-pin on the crank-arm, said pawl embodying a finger on one side of the crank-pin to extend into the channel recesses of the ratchet disc and a handle on the other side of the crank-pin to turn the pawl arm about the crank-pin, a leaf spring anchored on the crank-arm and engaging the pawl handle to bias the pawl finger into or towards the channel recesses of the ratchet disc, and a button-head mechanically connected to the crank-arm to rotate the arm, a coil spring in cooperative relationship with said pawl so as to be wound as the result of rotation of said button during voting, resetting means for engaging said pawl to allow unseating of said pawl from its corresponding ratchet recess, thereby allowing it to move in a direction opposite that in which it was rotated, under the influence of the energy stored in said wound coil spring and assume engaging relationship with a different ratchet recess in a position clear of said resetting means without affecting the position of said rotated shaft.

FRANK CONRAD.
